UNITED STATES PATENT OFFICE

GERALD S. HOWLAND, OF BROOKLINE, MASSACHUSETTS

METHOD FOR MAKING MULTICOLOR PRINTING PLATES

Application filed October 8, 1929. Serial No. 398,275.

This invention relates to a method for making multicolor printing plates for reproduction in color.

Heretofore in making plates of the foregoing character, it has been customary to take 5 a series of photographs of the subject using different color filters and a half tone screen turned at different angles to prevent patterning in order to secure negatives equal in number to the number of color plates to be made. 10 In taking these photographs, a prism is used in order to secure negatives with the images unreversed. From each negative a plate of suitable material permitting etching, such as 15 copper, covered with a sensitized coating, is printed which gives a positive impression of the subject with the image in reversed position so that when the plate is used for printing, the impression of the subject therefrom 20 will be in unreversed position. The plates so prepared are then etched in any suitable manner and are proven after each etching by taking a color impression therefrom and this process of alternate etching and proving is 25 continued until satisfactory results are attained. Since the etching in each case is a question of judgment and calls for the exercise of a high degree of skill, the number of those who are qualified to do this work is limited and skilled etchers or color engravers are 30 in great demand and receive large compensation.

This process of making plates is slow, tedious and very expensive. It is slow because 35 generally only one man can do the etching on a set of plates since he carries the color scheme in his mind and all the plates must be made in accordance with this scheme and the process is expensive because the great 40 skill and judgment required of the etchers commands very high wages. In spite of this skill, however, mistakes of judgment are not of infrequent occurrence and when any etching results in too much of the material of the 45 plate being removed it is thereby rendered valueless and the work has to be started over from the beginning. As a general rule not less than six days are required for the preparation of a set of four color plates and some- 53 times this period is extended to two or three

weeks according to the character of the subject and the plates. The work consumes much time with ever present possibilities of over-etching with the burden in such cases of throwing away the work and beginning the process anew. Another disadvantage of the 55 old method is that if a set of plates of a different size is required of the same subject, the entire method has to be repeated for each size of plate because the making of one sized set is of no assistance in turning out a different size and because of this fact another disadvantage creeps in, namely, that there is a difference between the final result secured in different sizes of sets of plates of the same 60 subject since it is simply impossible for the engraver to produce the same identical results in different sizes.

One of the important objects of the present invention is the provision of a method 70 of making multicolor plates which is more expeditious, more exact in results and cheaper.

Another object of the invention is the provision of a method by which certain steps are 75 obviated in the preparation of one or more sets of plates of the same subject differing in size from the original set so that additional sets of different sized plates may be produced at a greatly reduced cost.

A further object of the invention is the production of a method which does not require highly skilled etchers or color engravers to produce the desired results and thereby cuts substantially the labor costs in the preparation of the plates.

An additional object is the provision of a method which obviates most of the possibility of over-etching and thereby eliminates waste.

Other objects of the invention will be more specifically set forth and described herein-after.

In the accompanying drawings, there is shown a flow sheet to illustrate the procedure followed in carrying out my process for the reproduction of a subject in color by the use of four plates, in which Figure 1 shows the first four steps of the process beginning with the photographing of the subject using color 95 100

filters and Fig. 1a shows the last three steps ending with the printing of the reproduction by the use of the four plates prepared in accordance with my invention, that part of the flow sheet shown in Fig. 1a being a continuation of the flow sheet shown in Fig. 1. Following is a detailed description of the process shown in the accompanying drawings.

One of the essential features of my process consists in first preparing a set of prints in black and white of the subject, corresponding in number to the number of plates desired, which prints when retouched are used as a record from which any number of sets of plates of different sizes may be prepared. To secure this record a series of photographs of the subject are taken using any suitable photographic apparatus in order to obtain a series of negatives equal in number to the number of plates to be made. In taking this series one black and white view is taken without a color filter and the balance of the series are taken using different color filters. For example, if four plates are to be prepared, one photograph is taken without a color filter, one with a green filter which eliminates all colors in the subject except red, one with an orange-red filter eliminating all colors except blue and the last with a violet filter which cuts out all colors except yellow so that as a result of the four photographs, one has four negatives showing separately the black and white, the red, the blue and the yellow color values in the subject.

From the four negatives, a set of four prints in black and white is then made, said prints being mounted upon cardboard or other suitable support either in assembled relation or separately as desired. For making the prints any suitable photographic printing paper may be used but care must be taken to avoid any stretching of the paper when mounted on the support so that there will be perfect register in the finished plates. The prints or photographs are then retouched in black and white to bring out the effects desired or to emphasize some points and to minimize others, the artist supplementing the work of the filters, since color filters generally are only theoretically correct and do not always give absolutely correct results. The retouching corrects the deficiencies of the filters and the photography and in the retouching the artist has before him the subject as a criterion. If, in some cases the color filters produce satisfactory results, retouching may be avoided which might be true of cheaper classes of work but as a rule in the best work, retouching will be required. After the prints or photographs have been so treated they then form a permanent record from which any number of different sized sets of plates may be prepared.

To prepare plates from the record prints, a series of negatives is first made by photo-

graphing each print through a half tone or other screen of suitable mesh using a prism lens to secure the image on the negative in unreversed position. To prevent patterning the prints are turned at different angles when photographed, from each negative is taken a print on a plate of material suitable for etching or engraving, such as copper, said plate being coated with a suitable sensitized preparation for this purpose. Since the image on the negative is in unreversed position, the image on the plate will be a positive reversed in position so that impressions from the plate will appear unreversed and like the subject. The plate is then developed and is generally baked in the well-known manner to fix the image thereon.

The plates so prepared are then ready for etching or engraving and in this work the etcher or engraver follows the record prints to bring out in the plates the color values shown in the prints in black and white. This operation thereupon becomes merely a question of matching in the plate the light and shade values as shown in the record and this work does not call for the high degree of skill and judgment required in etching plates by the old process when the etcher or engraver had to carry in his mind in etching each plate the color scheme of the finished product, but can be adequately performed by operators whose pay is not more than half that called for by the old method. In preparing plates by this method the four plates, for instance, in four color work, can be given to four different operators, as each operator has merely the simple problem of treating the plate to bring out the values shown in his particular record print. It thereby becomes possible to produce a set of plates in a much shorter time than under the old method in which all the work had to be done by one man.

When the record prints are small in size they may all be mounted on one support of cardboard or other suitable material but in such case the prints are mounted at different angles to each other to prevent patterning being caused in the impressions taken from the finished plates due to use of the half tone or other kind of screen. When so mounted in assembled relation, all the prints may be photographed as a unit and all printed from the negative onto the sensitized plate in one operation thereby saving time, labor and materials. The plate either before or after being etched may be cut into the separate plates.

When one or more additional sets of plates of the same subject but of other size or sizes is or are required, they are prepared by photography from the record prints following the method hereinbefore described by either enlarging or reducing the sizes of the negatives in comparison with the record prints.

It is to be observed that the retouched prints which serve as a record operate as a control of the process which gives a most accurate measure of color values to facilitate the etching or engraving and an accuracy far greater than the old process.

The advantages of my method are first, that it eliminates the use of highly paid color etchers or engravers thereby greatly reducing the cost of the plates; secondly, the method can be carried out in a shorter time and is more expeditious and where the old method required six days or more for the production of a set of four color plates, the same may be produced within twenty-four hours from the preparation of the record photographs. I have found that the expense of preparing the first set of plates including the preparation of the record prints runs from thirty to thirty-five percent less than the preparation of the first set of plates under the old method and that the cost of preparing subsequent sets of different sized plates is reduced fifty percent over the cost of those plates prepared by the old method. Thirdly, because the retouching is done on the black and white photographs or prints, better results can be secured, the work can be done more easily and it can be done by women as well as men and in a much shorter time. In carrying out my method the results desired in the finished plates are shown on the record prints whereas under the old method it was done by the color engravers in the etching room working over acid and under unfavorable conditions.

My method will be found especially valuable in the making of plates such as are used in the chromium process where it is impossible to re-etch and the desired results must be attained in the first etching because my process practically makes unnecessary re-etching.

It is to be understood that my method is susceptible of use in making plates for reproducing by various other processes and that the plates may be of different materials and of different forms and where in the following claims I use the term "plate" I intend it to include plates either in flat, cylindrical or other forms.

What I claim is:

1. The method of making multicolor printing plates for reproduction in color consisting in making a series of photographic negatives, one in black and white and the others with color filters, said negatives corresponding in number to the number of plates desired, preparing a print from each of said negatives, retouching said prints to bring out in black and white the color values of the respective colors in the subject, then preparing photographic negatives of said series of prints, using a suitable half-tone screen and with a prism lens for securing upon said

negatives the images of said prints in un-reversed position, said prints being arranged at different angles when photographed to avoid patterning, then printing from said negatives upon sensitized plates suitable for etching and finally etching said plates to obtain the respective color values shown in said retouched prints.

2. The method of making multicolor printing plates for reproduction in color consisting in making a series of photographic negatives, one in black and white and the others with various color filters, said negatives corresponding in number to the number of plates desired, preparing a print from each of said negatives, then mounting said prints on a single sheet of suitable supporting material in close and angular arrangement to prevent patterning when photographed through a half-tone screen, then preparing a photographic negative of said series of prints, using a suitable half-tone screen with a prism lens for securing on said negative the images of said prints in unreversed position, then printing from said negative upon a sensitized plate suitable for etching, etching said plate to secure the respective color values shown in said retouched prints and finally cutting said etched plate to secure a series of plates equal in number to the number of retouched prints.

In witness whereof, I hereunto set my hand this seventh day of October, 1929.

GERALD S. HOWLAND.
